UNITED STATES PATENT OFFICE.

GUS SEDERSTRAM, OF FARRAGUT, IOWA.

LATCH.

1,246,950.

Specification of Letters Patent. Patented Nov. 20, 1917.

Application filed July 26, 1916. Serial No. 111,507.

To all whom it may concern:

Be it known that I, GUS SEDERSTRAM, a citizen of the United States, residing at Farragut, in the county of Fremont and 5 State of Iowa, have invented certain new and useful Improvements in Latches, of which the following is a specification.

This invention relates to certain new and useful improvements in latches.

10 The primary object of this invention resides in the provision of a latch which will be of simple construction and operation, as well as highly efficient in use.

A further object of the invention resides 15 in the provision of a latch of this character which will be composed of a minimum number of parts and in which the locking bolt may be readily turned after being withdrawn and engaged with the out-turned end 20 of the bolt supporting and guiding plate to hold the bolt in withdrawn position.

With these general objects in view and others that will appear as the nature of the invention is better understood, the same consists 25 in the novel combination and arrangement of parts hereinafter more fully described, illustrated in the accompanying drawings, and pointed out in the appended claim.

30 In the drawings forming a part of this application and in which like designating characters refer to corresponding parts throughout the several views:—

Figure 1 is an elevation of a dumping end 35 gate having my invention in operative position thereon, and

Fig. 2 is a fragmentary sectional view of the end gate, and showing a latch constructed in accordance with my invention 40 applied thereto.

Referring more in detail to the drawings, 1 designates the main board of the end gate and 2 the side members, while 3 designates the transverse brace bars mounted upon the 45 outer face of said main board 1. The dump board 4 is hinged to the central transverse brace bar 3 by suitable hinges 5 and serves when in closed position to close the opening 6 in the lower portion of the main board 1.

50 Suitable metallic plates 7 are secured upon the ends of the lower transverse bar 3 and provided with outwardly directed apertured ends 8 adjacent the sides of the opening 6, it being understood that the central portion 55 of the lower transverse brace bar 3 is sepa-

rated from the ends thereof and secured to the outer face of the dump board 4, a short distance from the lower end of the latter. It will also be understood that an additional central brace bar 3 is secured to the end gate 60 with the main or central portion of said additional central transverse brace bar mounted upon the dump board 4 and the ends of the same projecting past the sides of said dump board 4 as clearly shown in Fig. 2 of 65 the drawings.

The above construction is recited for the purpose of illustrating the application of my latch, two of which are shown in this instance. The latch consists of a bolt-supporting and guiding plate 9 which has its outer end bent back upon the main portion of the plate 9 and extended outwardly, as shown at 10. The opposite end of the plate 9 is also extended outwardly as at 11, and 70 in parallelism with the part 10. The outwardly directed ends 10 and 11 are provided with registering openings to accommodate the bolt 12. An expansible spring 13 encircles the bolt 12 between the ends 10 and 11 of the plate 9 and has one end positioned against the end 11 while its opposite end bears against the pin 14 engaged through the bolt 12. This pin 14 also serves to limit the movement of the bolt 12 in one direction. 75 The bolt is preferably formed of a single bar of metal having one end bent to provide a loop or hand engaging member 15. The bolt 12 may be held in retracted position by rotating the same after it has been retracted, until the loop 15 abuts the part 11 of the plate 9. As soon as the loop 15 is released from the ends 11 of the plates 9, however, the spring 13 will project the bolt 12 outwardly and through the apertured 80 end 8 of the plate 7, assuming dump board 4 to be in closed position. The forward end of the plate 9 is provided with an aperture 16 through which the end 8 of the plate 7 projects when the dump board 4 is in closed 85 position.

This embodiment of the invention is merely illustrative and I wish to here state that the construction herein disclosed may be modified in many different respects that 105 may be fairly embodied in the scope of the appended claim.

What I claim as new is:—

A latch comprising a keeper plate having an out turned end which is provided with 110

an opening, a plate having one end extended outwardly and its opposite end portion bent upon itself, the extreme end of this end portion being extended outwardly in parallelism with the other out turned end, said end portion being provided with an opening to accommodate the out turned end of the latch plate, and a spring pressed bolt 5 slidable through the out turned ends of the

plate and the opening in the out turned end of the latch plate.

In testimony whereof I affix my signature in presence of two witnesses.

GUS SEDERSTRAM.
